UNITED STATES PATENT OFFICE

SAMUEL I. BERGER, OF NEWARK, NEW JERSEY

MECHANICAL TOY

Application filed June 8, 1925. Serial No. 35,543.

My present invention relates to improvements in mechanically driven figure toys of the class in which a plurality of manikins are operated simultaneously from a single source of power, and through a single actuating means, and in which the toy figures cooperatively simulate a pair of contesting athletes, such for instance as the principals in a boxing bout.

10 An object of the invention is to produce a realistic toy of this character, which will be of attractive appearance, and simple, durable construction. A further object is to so operate the figures, that their movements, while following a general predetermined sequence, will nevertheless be sufficiently irregular and variable to avoid the common fault of monotonous and timed regularity which would detract from the life-like effect.

15 In a preferred embodiment of the invention the two boxing figures are disposed upon opposite ends of a transversely yieldable supporting member, the middle of which is intermittently operated to cause the toy figures which are sufficiently heavy for the purpose, to bob resiliently by flexing the supporting member. Preferably the supporting member is secured at its middle to the upper end of a vertical actuating rod, which is vertically reciprocated at irregularly timed intervals, and intermittently rotated at irregular periods. The toy figures are equipped with freely swinging arms and legs, moved by inertia as the various movements of the supporting means are transmitted directly to the figures. The legs may also be caused to swing by contact with the floor as the toy figures move up and down and circle about each other.

20 The motive power is preferably derived from a spring motor of the same general character as that disclosed in my copending application, Serial No. 17,162 filed March 21, 1925.

25 The motor is preferably equipped with an unusually simple, easily operated effective braking mechanism.

30 Other features of the invention are the construction of the toy figures, and the construction of the diminutive representation of a

prize ring, within which the figures perform their antics.

In the accompanying drawings, Figure 1 is a view in side elevation of the toy, parts being broken away and in section for clearness.

35 Figure 2 is a sectional view taken on line 2—2 of Figures 1 and 3.

Figure 3 is a view in transverse section on the line 3—3 of Figure 2,

40 Figure 4 is a similar view on the line 4—4 of Figure 2, and

Figure 5 is a fragmentary perspective view indicating a modified type of ring.

45 The motor housing includes side walls 10, a bottom 11, and a top 12, the latter serving as the floor of the ring. In the form shown in Figs. 1 to 4, the member 12 is formed with upturned marginal flanges 13, having their ends connected together as by bendable metal tongues 14. Upon the flanges 13, there is lithographed, painted or otherwise depicted the representation of ropes 13' and corner posts.

50 The motor is preferably of the general construction shown in my copending application above referred to and includes a torsion spring 15 encircling a revolving drum 16 which carries a driving gear 17. The gear 17 drives a train of speed increasing gears 18, 19, 20 and 21 which act by inertia to exert a fly wheel effect upon the motor. The first and third gear of this train are mounted upon a power shaft 22, and the second and fourth are journaled on a counter shaft 23. A key 24 serves for manually winding the 55 motor spring and a ratchet and pawl mechanism prevents retrograde unwinding thereof. The operation of the ratchet wheel 25 and the eccentrically pivoted pawl 26 are fully set forth in my copending application above referred to.

50 The brake lever includes a handle end 27, lying flat against the outside of the motor casting, an offset intermediate portion 28 extending through the casing wall, constituting a pivot for the brake lever. The inner end of the brake lever is offset at 27° and adapted to engage with teeth of the gear wheel 21 to hold the entire train against movement. The lever is of flat wire stock and has its greatest 60

width or stiffness in the plane of its pivotal movement: The wall 10 has an embossment 10' thereon in the path of lever 27 which positively limits shifting of the lever from both the braking and the releasing setting. The direct and positive action of the brake is manifest.

The rotatable and vertically reciprocable actuating rod 29 is mounted in bearings 29^a, 29^b and extends upward through an opening 30 in the platform 12. Rod 29 carries a collar 31, within the motor casing, said collar being preferably in the nature of a roughly toothed pinion. Carried by one end of the power shaft 22 are a plurality of radially disposed lifting fingers 32, which, as the shaft rotates, intermittently strike the lower face of the pinion 31 and bodily elevate it together with the actuating rod to which it is attached. The lifting fingers are spaced at irregular intervals about the power shaft so that the reciprocation of the actuating rod is not only intermittent but variably timed. The fingers 32 engage the teeth of the pinion 31 and thereby effect rotation of the actuating rod, but inasmuch as the teeth of the pinion are not cut with any attempt at accuracy and also since the jogging and swinging by momentum of the figures also affects the turning of the rod, the latter is moved no predetermined distance at each reciprocation. Teeth of the descending pinion straddle the edge of a stationary plate 10^a which provides the bearings for one end of shafts 22, 23. The rotational movement of the figures by momentum after the impetus given by the lifting fingers is thus checked. The rotary movement of the pinion takes place only when it is at the level of cut away part 10^b. Upon the upper end of the rod 29 I secure the intermediate portion of a horizontally disposed supporting member 35, preferably a flat spring or some similarly yieldable device. Upon the ends of the spring 35 are mounted the toy figures 36, 36. These figures preferably include integral head and body portions formed by interlocking bendable tongues 37 at the edges of a pair complementary metallic portions, which may be integrally joined at the top of the head. Other tongues 38 at the base of the body, pass through openings 39 in the ends of the spring 35 and retain the figures in place on the support. Other tongues 40, 41 at the shoulders and hips of the figures offer pivotal mounting for the free swinging arms and legs 42, 43 these tongues being enlarged at their outer ends to determine the possible lateral displacement of the pivoted ends of the limbs. The operation will be evident from the foregoing description. As the actuating rod is reciprocated and rotated, the support spring 35 is concurrently moved up and down, and caused to rotate about its middle. The figures are reciprocated with the sup-

port, but by reason of their weight, they flex and sway the spring support and thus bob resiliently in a manner simulating a boxing contest especially as the arms and legs will pivot freely during this movement. The legs, moreover, are caused to strike the floor when the rod 29 is dropped by the lifting fingers 32 following each rise of the pair of figures. The effect produced is strikingly life-like and realistic. The boxers circle, 75 dance and spar with remarkable agility although no blows are actually struck.

In Fig. 5 I have illustrated a modification in which the flanges 13 of the platform are omitted and the ring is simulated mechanically rather than pictorially. Angular brackets 50 are superposed over the corners of the platform 51 and protrude therebeyond. The bracket has an integral median arm 57, extending into a pocket 57' upstruck from the platform and tongues 52 cut out of the platform are superposed over the sides of the arm 57. The bracket 50 has a socket opening 53 to receive the corner post 54. The latter is formed of a cylindrically shaped metallic sheet having intermediate its ends, a struck out tongue 55 adapted to embrace and retain the corresponding part of the rope 56, which extends about the four identical posts at the corners of the platform.

It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having thus described my invention what I claim as new and desire to secure by Letters Patent is:

1. In a toy of the class described, a vertically disposed intermittently rotated actuating rod, a horizontally disposed supporting member secured intermediate its ends to the upper end of the rod, said member resilient in a vertical plane and rigid in a horizontal plane and figures mounted on the ends of the supporting member and including freely swinging limbs.

2. In a toy of the class described, a vertically disposed actuating rod, a horizontally disposed supporting member resilient in a vertical plane and secured intermediate its ends directly upon the upper end of the rod, figures mounted on the ends of the supporting member and including freely swinging

limbs, and means for intermittently rotating the rod at irregularly timed intervals.

3. In a toy of the class described, a vertical actuating rod, a resilient horizontal supporting member secured intermediate its ends to the upper end of the rod, toy figures secured to the ends of the supporting member and including freely swinging arms and legs, means for vertically reciprocating the rod at irregularly timed intervals, and means for intermittently rotating the rod at irregularly time intervals.

4. In a toy of the class described, a motor casing, a motor therein, a platform covering the casing, a vertically disposed actuating rod projecting upward through the platform and operatively connected to the motor for intermittent reciprocating and rotational movement thereof, a flat spring mounted at its middle on the upper end of the actuating rod, and toy figures secured to the ends of the spring, said figures including freely swinging arms and legs.

5. In a toy of the class described, a motor casing, a motor therein, a platform covering the casing, a vertically disposed actuating rod projecting upward through the platform and operatively connected to the motor for intermittent reciprocating and rotational movement thereof, a flat spring mounted at its middle on the upper end of the actuating rod, and toy figures secured to the ends of the spring, said figures including freely swinging arms and legs, the legs being arranged to contact with the platform at one end of the reciprocating stroke of the rod.

6. In a toy of the class described, a motor casing, a motor therein, a platform covering the casing, a vertically disposed actuating rod operating upward through the platform, a flat spring mounted at its middle upon the actuating rod, toy figures secured to the ends of the spring and including freely swinging arms and legs, said spring having slots there-in and tongues on the body of each figure interlocking with the slots.

7. In a toy of the class described, a motor casing, a motor therein, a platform overing the casing, a vertically disposed actuating rod projecting upward through the platform and operatively connected to the motor for intermittent reciprocating and rotational movement thereof, a flat spring mounted at its middle on the upper end of the actuating rod, and toy figures secured to the ends of the spring, said figures including freely swinging arms and legs, the figures being sufficiently heavy to flex the spring as the rod is reciprocated.

8. As a new article of manufacture, a toy figure including a body and head portion formed of interlocking complementary stamping portions, tongues at the lower end of the body adapted to interlock with a support and freely swinging flat limbs pivoted to

the body, said body having tongues projecting laterally therefrom upon which the limbs are pivoted.

9. As a new article of manufacture, a toy figure including a body and head portion formed of interlocking complementary stamping portions, tongues at the lower end of the body adapted to interlock with a support and freely swinging flat limbs pivoted to the body, said body having tongues projecting laterally therefrom upon which the limbs are pivoted, said tongues having enlarged outer ends to retain the limbs against loss.

10. In a toy of the class described, a pair of supported manikins including freely swinging arms and legs, means for causing the manikins to jump up and down and swing their arms and legs, means for causing the manikins to circle about a predetermined path while maintaining a predetermined relationship to each other and means for irregularly timing all of the movements of the manikins.

11. A toy of the class described, a motor casing, a platform constituting a top for the casing and having an opening therein to accommodate the operating connections between the motor and figures on the platform, detachable brackets projecting beyond the corners of the platform, upright posts secured in the brackets and a flexible device connecting the posts.

12. In a toy of the class described, a motor casing, a platform constituting a top for the casing and having an opening therein to accommodate the operating connections between the motor and figures on the platform, brackets interlocked with and projecting beyond the corners of the platform and having post holes, corner posts secured in said post holes and a flexible device connecting the corner posts.

13. In a toy of the class described, a motor casing, a platform constituting a top for the casing and having an opening therein to accommodate the operating connections between the motor and figures on the platform, brackets interlocked with and projecting beyond the corners of the platform and having post holes, corner posts secured in said post holes and a flexible device connecting the corner posts, said brackets and platform being interlocked by bendable tongues.

14. In a toy of the class described, a motor casing, a platform constituting a top for the casing and having an opening therein to accommodate the operating connections between the motor and figures on the platform, brackets interlocked with and projecting beyond the corners of the platform and having post holes, corner posts secured in said post holes and a flexible device connecting the corner posts, said posts including outstruck metal tongues receiving and clamping the flexible device at each corner of the platform.

15. A device of the class described including a motor casing, a spring motor housed within the casing, and including a train of speed increasing gears acting by inertia to exert a fly wheel effect on the motor, a brake lever disposed in the plane of one wall of the casing and including an offset intermediate portion having limited pivotal movement in the wall, opposite ends of the lever being disposed on opposite sides of the wall and the inner end thereof being engageable with the teeth of one of the gear train to lock the same against movement.
16. In a mechanical toy, a substantially T shaped structure, the upright of which constitutes an intermittently rotated actuating rod and the cross bar of which is resilient in a vertical plane, and rigid in a horizontal plane, and toy figures detachably mounted upon the ends of the cross bar and including freely swinging arms and legs.
17. A device of the class described including a motor casing, a spring motor housed within the casing, and including a train of speed increasing gears acting by inertia to exert a fly wheel effect on the motor, a brake lever disposed in the plane of one wall of the casing and including an offset intermediate portion having limited pivotal movement in the wall, opposite ends of the lever being disposed on opposite sides of the wall and the inner end thereof being engageable with the teeth of one of the gear train to lock the same against movement, said casing wall having a projection outstruck therefrom in the path of movement of a part of the lever to prevent accidental movement of the outer end of the lever to or from locking position.
40. Signed at Newark, in the county of Essex and State of New Jersey, this 4th day of June, A. D. 1925.

SAMUEL I. BERGER.
